Inventor,

Frank H. Jensen;

By A. B. Leapham,
Attorney.

UNITED STATES PATENT OFFICE.

FRANK H. JENSEN, OF EVERETT, MASSACHUSETTS.

ANKLET AND ARCH RETAINER.

Application filed August 10, 1922. Serial No. 500,976.

To all whom it may concern:

Be it known that I, FRANK H. JENSEN, a citizen of the United States, residing at Everett, in the county of Middlesex and State of Massachusetts, have invented certain new and useful Improvements in Anklet and Arch Retainers, of which the following is a specification.

This invention has for its object the construction of an anklet and arch retainer that shall give equal distribution of the body's weight to the bones of the foot, elevate any displaced bones to their proper positions, and prevent swelling and puffing immediately below the ankle.

To this end I have produced an elastic anklet adapted to embrace both the ankle and foot, providing it with tapes designed to aid in giving correct posture in standing and walking, and also with pad-receiving pockets for elevating the scaphoid bone to prevent its sagging and dropping on the main arch, and also to elevate the metatarsal bones, the whole not only serving the above recited functions but others to be hereinafter described.

In the drawings forming part of this specification, Fig. 1 is a side view of a person's foot and lower limb showing the same provided with an anklet and arch supporter embodying my improvements. Fig. 2 is a view of the same from below showing it nearly full size. Fig. 3 is a cross section on the line 3—3 in Fig. 2.

In the fabrication of the device, I take an elastic fabric woven with the elastic strands all extending in one direction so that it will stretch one way only, and so cut and stitch it together as to bring its seams at the rear of the leg portion 1, at the sides of the ankle portion and along one side of the foot portion 2, at the inner side thereof. These seams are covered and reinforced by tape 3 and 4. An opening 5 is provided for the heel of the wearer, a separate piece of the fabric being stitched to the main portion immediately above the heel-opening, at 6.

To the sole portion 7 of the fabric is stitched a single piece of leatherette 9 to form two pockets 10 and 11, the pocket 10 being disposed to lie close in front of the heel and toward one side to come mainly beneath the inner portion of the arch of the foot, and the pocket 11 being longitudinally arranged to open at the front edge

of the foot portion 2. Into each of these pockets is introduced a felt pad 12 or 13, the pad 12 in the pocket 10 being somewhat short, but the pad 13 being comparatively long.

It will be observed that the pad 13 comes beneath the outer portion of the foot and serves to support the metatarsal bones from grading down on the nerve, and thereby to prevent callouses on the ball of the foot. The pad 12 elevates the scaphoid bone and keeps it from sagging upon the main arch. The anklet portion 1 prevents swelling and puffing below the ankle, assists nature where sprains thereat have occurred, eliminates pains in the ankle and the calf of the leg, and as a whole it prevents distortion in the leg and foot in general.

Further, the elastic material by its described arrangement affords direct compression for varicose veins, relaxed muscles, so-called milk ankle, and the like. The arrangement of the tape on the back and sides aids in giving reinforcement to correct posture in standing and walking, and in providing smooth locomotion, and provides a support for the tendon achilles.

What I claim is:

1. An anklet and arch retainer comprising elastic fabric fitted to clasp the foot and ankle and having two pockets attached to the foot portion, one at the front end and the other at the side opening to the inner side of the foot, and yielding pads removable inserted in said pockets.

2. An anklet and arch retainer comprising elastic fabric fitted to clasp the foot and ankle, and a fabric attached to the sole of the foot portion to form two pockets, one pocket opening toward the inner side of the foot close in front of the heel, and the other pocket opening toward the front of the foot portion beneath the joints of the smaller toes of the foot.

3. An anklet and arch retainer comprising elastic fabric fitted to clasp the foot and ankle, a length of tape stitched to the rear upper portion and to the side of the foot portion, and two pads removably secured to the sole of the foot portion, one pad being beneath the arch of the foot and the other beneath the toe-joints.

In testimony that I claim the foregoing invention, I have hereunto set my hand this 28th day of July, 1922.

FRANK H. JENSEN.
